US0D1073849S

(12) **United States Design Patent** (10) Patent No.: **US D1,073,849 S**
(45) Date of Patent: ** May 6, 2025

(54) **WEAPON SIGHT**

(71) Applicant: **Crimson Trace Corporation**,
Columbia, MO (US)

(72) Inventors: **William A. Planck**, Columbia, MO
(US); **Tim Meissen**, Columbia, MO
(US); **Shane Ball**, Columbia, MO (US);
Michael Cottrell, Ashland, MO (US);
Ryan Donahue, Columbia, MO (US);
John Oller, Columbia, MO (US)

(73) Assignee: **Crimson Trace Corporation**,
Columbia, MO (US)

(**) Term: **15 Years**

(21) Appl. No.: **29/792,941**

(22) Filed: **May 2, 2022**

(51) LOC (15) Cl. **22-01**

(52) U.S. Cl.

USPC **D22/109**

(58) **Field of Classification Search**

USPC D16/130, 132, 133, 220; D21/572-574;
D22/108, 109, 110, 199; D26/38, 60

CPC F41G 1/00; F41G 1/32; F41G 1/35

(57) **CLAIM**

The ornamental design for a weapon sight as shown and described.

DESCRIPTION

FIG. 1 is a perspective view of a weapon sight;

FIG. 2 is a rear view thereof;

FIG. 3 is a right side view thereof;

FIG. 4 is a top view thereof;

FIG. 5 is a front view thereof;

FIG. 6 is a left side view thereof; and,

FIG. 7 is a bottom view thereof.

The broken lines depict portions of the weapon sight that form no part of the claimed design.

1 Claim, 7 Drawing Sheets
